UNITED STATES PATENT OFFICE.

THEODORE F. GOODRICH, OF ALBANY, NEW YORK, ASSIGNOR TO THEODORE F. GOODRICH, AUGUST ROMMEL, AND GUSTAV ROMMEL, DOING BUSINESS UNDER THE NAME OF GOODRICH, ROMMEL COMPANY, A COPARTNERSHIP.

GUIDE-GREASER FOR ELEVATORS.

No. 902,226.

Specification of Letters Patent.

Patented Oct. 27, 1908.

Application filed December 7, 1907. Serial No. 405,472.

To all whom it may concern:

Be it known that I, THEODORE F. GOODRICH, a citizen of the United States, and a resident of the city and county of Albany, State of New York, have invented a new and useful Improvement in Guide-Greasers for Elevators, of which the following is a specification.

The object of my invention is to provide a device of this class, which will accurately and reliably grease the guides of elevators and also indicate the amount of grease in the device. This object is accomplished by my invention, one embodiment of which is hereinafter described.

For a more particular description of my invention, reference is to be had to the accompanying drawings forming a part hereof in which

Figure 1 is a perspective view of my improved lubricator. Fig. 2 is the longitudinal section of the same taken on the line 2—2 of Fig. 3. Fig. 3 is an end elevation of the same. Fig. 4 is a side elevation of an elevator with my improved lubricator applied thereto.

Throughout the various views of the drawings similar reference characters designate similar parts.

My improved lubricator 1 is attached to an elevator 2, and at any part thereof conveniently located near the guides 3, and preferably placed on top of the cage as shown in Fig. 4. It is preferably secured in place by means of a bracket 4, which consists of a slotted base 5, adapted to receive and hold screws or other fastening devices and extending at right angles to the base 5 is a pedestal 6, which is provided with a clamp 7, at its other end and which is adapted to hold and secure the lubricator 1. This lubricator 1 comprises a cylindrical shell 8 one end of which is slotted at 9 to receive a guide 3 and on each side of this slot 9 the walls are inclined as shown at 10. The other end of the shell 8, is provided with a head 11, which is fitted to said shell by

means of screw threads and the center of this head is perforated to permit the shank 12 of a follower to pass therethrough. The outer end of the shank 12 is provided with a head 13 secured in any suitable manner and the inner end is provided with a disk 14, which fits snug in the tube 8. A coiled spring 15 rests in the bore of the tube 8 and has one end against the disk 14 and the other against the head 11, and this coiled spring 15 surrounds the shank 12.

When my improved lubricator is used, the head 11 is first removed and the lubricant in the form of a candle or packed grease is placed therein. The disk 14, is then put in position in the bore of the tube 8 and the head 11 is secured in place thereby placing the spring 15 under tension, thus forcing the lubricant against the guide 3. The position of the head 13 of the shank 12, indicates to an observer the amount of grease in the lubricator so that from time to time this grease may be renewed as may be necessary or expedient.

Various other embodiments of my invention may be made all of which embody its essential features and characteristics.

Having thus described my invention, what I claim is,

In an article of the class described, a lubricator for elevators and the like comprising a cylinder having a slot at one end, inclining walls on each side of said slot, a cap at the other end of said cylinder, a follower and a spring between said follower and said cap, whereby the lubricating material is forced through said slot by said follower and by the inclined walls so that three sides of the guide may be lubricated simultaneously.

In witness whereof, I have signed my name to this specification in the presence of two subscribing witnesses.

THEODORE F. GOODRICH. [L. s.]

In presence of—

GUSTAV ROMMEL,
CLARENCE ASCHER.
